UNITED STATES PATENT OFFICE

CARL BROWN, OF DENVER, COLORADO, ASSIGNOR TO THE CHAMPION FORGING MACHINE COMPANY, OF DENVER, COLORADO, A CORPORATION OF COLORADO.

SHARPENING-DIES FOR ROCK-DRILLS.

1,053,476.

Specification of Letters Patent.

Patented Feb. 18, 1913.

Application filed August 2, 1909. Serial No. 510,952.

To all whom it may concern:

Be it known that I, CARL BROWN, a citizen of the United States, residing in the city and county of Denver and the State of Colorado, have invented new and useful Improvements in Sharpening-Dies for Rock-Drills, of which the following, together with the accompanying drawings, constitutes a full, clear, and an exact specification.

10 This invention relates to dies for sharpening, or renewing, the chisel edges on the working face of a cruciform drill bit, such as is generally used in rock drilling, when these edges have become rounded and dull 15 from continued wear. These dies are intended to be furnished principally with the machine for making and sharpening rock drills and for general forging, upon which I have filed an application for U. S. Patent, Serial 20 No. 510,950, bearing even date herewith.

The object of the present invention is to provide a tool for sharpening the chisel edges on rock drills, more quickly and efficiently than is done at present and without 25 the necessity for skilled hand labor.

While the primary purpose is to use this invention in connection with the machine referred to, yet these dies may be mounted in an individual framework and used separately in cases where this may seem desirable. The present drawings show these dies as forming a part of the machine above mentioned, but any skilled designer of machinery can readily see how to construct a 30 simple individual framework containing the necessary elements for a separate machine.

In the accompanying drawings, Figure 1 is a front elevation of the dies in the working position. Fig. 2, is a view similar to 40 Fig. 1, but showing a drill in section while being operated upon by the dies. Fig. 3, is a partial section on line 3-3, Fig. 1, and Fig. 4, is a section on line 4-4, Fig. 1. Figs. 5 and 6, are views upon line a-b 45 looking respectively in the directions of arrows 56 and arrows 65. Fig. 7 is a side view of the point of a cruciform drill bit after its face edges have become rounded and dulled.

50 Referring to the drawings, (3^a) and (3^b) are parts of the tool wheel disks of my machine, the sleeves (3^c) and (3^d), extending outward, respectively, from (3^a) and (3^b). In constructing an individual machine, the parts (3^a) and (3^b) would form a portion

of the framework of the machine and these two parts would, of course, be rigidly connected to each other, so as to allow the proper working of the dies. The block (17^b) is the relatively stationary part of the dies and is secured in the sleeve (3^d) by pins (17^a). Two shanked rolls (4) and (5) are movably held in corresponding recesses of (17^b) and are so placed that they do not quite touch each other along elements of 60 their larger cylindrical parts. (4) and (5) have beveled abutments (4^a) and (5^a) across their front faces, these abutments assisting in giving the proper shape to the face of the drill.

(17^b) is channeled in front of the rolls (4) and (5) to admit one wing of the drill, allowing its face to just enter between (4) and (5).

(17^a) is the movable part of the dies and 70 is held normally in the retracted position by the spring (6), which is in compression between pins (3^c) and (17^a).

(7), (7), are movable jaws engaging the dovetailed projections (17^x), (17^x), which latter extend along the V-shaped face of (17^a), to either side of its vertex. The effect of the inclines between (17^a) and (7), (7), is to cause the movement, outwardly, of (7), (7) when (17) is driven forward.

(17^y) is a foot projecting from (17^a) back of (7), (7), to form a guide and bearing for the latter. Flat springs (17^s), (17^s), serve to keep the jaws (7), (7), normally closed. Along the adjacent sides of 80 (7), (7), and centered on their line of parting, is a channel with V-shaped bottom adapted to receive one wing of the cruciform. Along the faces of (7), (7), are beveled abutments (7^a), (7^a) corresponding to 85 abutments (4^a) and (5^a) previously named.

In using these dies, the dull drill is inserted from the front as shown by arrow (24), Fig. 3, its cruciform face resting along the various beveled abutments and in the 90 channels at right angles to the abutments. When (17^a) is struck by the hammer (5^x) and thereby forced against two opposite wings of the drill, it causes the jaws (7), (7), to be resisted by the drill wings and the 95 pressure exerted between the inclined faces causes (7), (7) to move outward, at the same time drawing the metal of the drill wings away from the center of the drill, and forging the dull drill gradually to the shape in- 100 105 110

dicated by the dotted lines in Fig. 7. When the dull drill is first inserted into the dies, its rounded face bears on the extreme and adjacent sides of abutments (4^a) and (5^a), 5 causing a one sided pressure on each, and (4^a) and (5^a) assuming the positions shown in dotted lines in Fig. 6. When the jaws (7), (7), draw the drill wings outward, this 10 action serves to gradually bring (4^a) and (5^a) back into line, the faces of the drill wings being practically hammered between the beveled abutments (4^a) and (7^a), and (5^a) and (7^a), forming a sharp chisel edge 15 across the face of the two opposite drill wings. The same operation is repeated on the two remaining drill wings.

An anvil block (9), back of the stationary die, is provided for taking up the shock produced by the striking of the hammer (5^x).

20 Having fully described my invention, what I claim as new, is:—

1. In sharpening dies for rock drills, the combination with a suitable frame, of a die block and a suitably guided, reciprocating 25 carriage, rolls, adjacent and approximately tangent to each other and socketed in the said die block, spring pressed abutment jaws slidably held along inclined faces on the said carriage, means for driving the said carriage forward and means for automatically retracting the said carriage.

2. In sharpening dies, the combination with a relatively stationary die block, having two adjacent and to each other approximately tangent shaping rolls socketed therein, a movable carriage adapted to be reciprocated in suitable guides, with two movable, spring-pressed, spreading jaws carried by the said carriage, means for driving the said 35 carriage forward and means for automatically retracting said carriage.

3. In sharpening dies, the combination with a suitable frame, of a relatively stationary die block, with two longitudinal adjacent rolls, suitably journaled therein, the 45 said rolls being adapted to form a V-face on the wings of a rock drill, when the said

rock drill is forced into the valley existing between the two rolls, a reciprocating carriage moving in guides held by the first 50 mentioned framework, two movable jaws mounted on the said carriage, the said jaws and carriage having inclined faces and guides, means for driving the carriage against the die block, and means for retracting the carriage. 55

4. In sharpening dies for rock drills, the combination with a relatively stationary die block, suitably supported, of a movable carriage suitably mounted, two longitudinally 60 adjacent rolls, journaled in the die block, the protruding faces of the said rolls having beveled abutment faces, two movable jaws (with beveled abutment faces) mounted on the said carriage, with means for causing 65 the said movable jaws to move laterally outward, when the said jaws are forced against the said rolls, means for forcing the said carriage forward and means for retracting the said carriage, as specified. 70

5. In sharpening dies, the combination of two principal, relatively to each other, approachable members, with suitable formers carried by each of the said members, the formers being so placed that their operating 75 faces oppose each other, the formers in the first of the said principal members, consisting of two rolls, longitudinally adjacent to each other and suitably journaled in the first principal member; the formers in the second 80 principal member, consisting of two movable jaws, having suitable faces to coöperate with the faces of the said opposing rolls, and means for moving the said jaws laterally across the faces of the opposing rolls, 85 when the said jaws are forced against the said rolls, as, and for the purpose specified.

In testimony whereof, I have signed my name to this specification in the presence of two subscribing witnesses.

CARL BROWN.
